UNITED STATES PATENT OFFICE.

JOE ERLICH, OF CHICAGO, ILLINOIS, ASSIGNOR OF ONE-HALF TO WILLIAM ROCHELLS,
OF CHICAGO, ILLINOIS.

AUTOMOBILE-RADIATOR.

1,278,892.

Specification of Letters Patent. Patented Sept. 17, 1918.

Application filed June 14, 1916. Serial No. 103,617.

To all whom it may concern:

Be it known that I, JOE ERLICH, a citizen of the United States, residing at Chicago, in the county of Cook and State of Illinois, have invented a certain new and useful Improvement in Automobile-Radiators, of which the following is a specification.

My invention relates to an improved construction of radiators adapted particularly for use on automobiles for cooling the water used in the jackets of the engine. My improvement contemplates an improved construction of radiators of the class referred to of the so-called "honeycomb" type, and by means of my improved construction I am able to readily remove from the radiator as a whole any desired section which may be giving trouble so as to substitute a perfect section therefor without interfering with the remaining portions of the radiator.

A preferred embodiment of my invention is shown in the accompanying drawings, in which—

Figure 1 shows in elevation the complete radiator structure,

Fig. 2 shows in enlarged elevation a portion of the water tubes and their connection to the upper header of the radiator,

Figs. 3, 4 and 5 are detail sectional views of the parts shown in Fig. 2, taken along the lines 3—3, 4—4 and 5—5, respectively, and

Fig. 6 shows in developed view a portion of one of the sheets used in forming the water tubes of the radiator.

Similar numerals refer to similar parts throughout the several views.

As shown in Fig. 1, the radiator consists of upper and lower headers 10 and 11 between which a plurality of water tubes 12 extend vertically. The construction of the water tubes and their manner of connection to the upper and lower headers 10 and 11 is best shown in Fig. 2, to which reference is made. Each water tube 12 is formed from two sheets of thin metal 13, cut so as to have extending flaps 14, 15 and 16 arranged in series along each edge, the width of the sheet being the same as the depth of the radiator from front to rear. After the sheets are cut as referred to, the edges thereof are bent or rolled to form outwardly opening channels 17 for a purpose to be described. The sheets are then folded along

the lines 18, 19, 20 and 21 so as to form horizontally extending pockets from the side of the sheet as shown at 22 in Fig. 2. The flaps 14, 15 and 16 are folded over each other as shown in Fig. 2 to close the ends of the pockets 22. The upper and lower ends of each sheet 13 are bent and extend horizontally as shown at 23 for a distance somewhat less than one-half of the width of the pockets 22, and on their ends outwardly opening channels 24 are formed for a purpose to be described. The portion 23 of the sheets of metal have formed on their edges outwardly opening channels 25 also for a purpose to be described.

The sheets of metal thus formed with their outwardly opening channels and projecting pockets are assembled in pairs by sliding narrow strips of thin sheet metal 26, having inwardly opening channels on their edges over the outer walls of the channels 24, so that the said channels interlock with each other, in which position the parts may be secured together by running solder into the channels 24. The width of the pockets 22 is such that they just fill the space between the assembled pair of sheets and, as indicated in Fig. 1, the pockets formed on one sheet alternate with those formed on the other, so that the air spaces formed between the sheets and the pockets are rectangular and of the conventional so-called "honeycomb" construction. Each pair of sheets 13 thus assembled constitutes a separate unit of the radiator, and several of these units are connected together to form the entire radiating structure by means of narrow strips of thin sheet metal 27 formed similarly to the strips 26 and engaging the channels 17 in a manner similar to the engagement between the strips 26 and the channels 24, the parts being preferably held together by solder run into the channels 17.

The radiating portion of the construction as a whole is secured to the front and rear portions of the header 10 by narrow strips 100 of thin sheet metal 28 formed similarly to the strips 26 and engaging the channels 25 and outwardly opening channels 29 formed along the lower edges of the front and rear walls of the header 10, the parts 105 being preferably held together by solder.

To protect and reinforce the outside sheets 13, I find it desirable to employ outer flat

sheets of thin metal 30 having outwardly opening channels 31 formed along their edges. Connecting strips 31' similar to the strips 26, 27 and 28 engage the channels 31 and the channels 17' formed on the edges of the sheets 13', so as to close the open spaces between the edges of the sheets 13' and 30 and provide outer empty shells for protecting the water tubes. The ends of these empty shells are closed by strips of thin metal 31^a, soldered in place. The upper and lower ends of the sheets 30 are provided with outwardly opening channels 32, similar channels 33 being formed along the lower edges of the side walls of the headers, these channels being engaged by narrow strips of thin sheet metal 34 formed similarly to the strips 26 and secured in place in said channels by means preferably of solder.

It will be understood that the radiating portion of the construction is connected to the upper and lower headers in the same manner, as a result of which it is unnecessary to show more than the parts illustrated in Fig. 2; and that the sheets 13 used in forming each radiator unit are of the same construction and may be made by means of the same dies and forming devices so that all of the bent sheets 13 and 13' require but a single set of tools to manufacture them.

As a result of the construction described, when it is necessary to repair a radiator built according to my invention, the defective section may be separated from the remaining portion of the radiator and removed by cutting through the strips 27, 28, 31' and 34 with a knife or other instrument, after which the sheets of the removed section may be separated, if desirable, by cutting through the strips 26. The edge portions of the cut strips are then readily removable from the channels by the application of heat to melt the solder, and a perfect sheet or section may be put in place and the radiator made as good as new by again connecting the parts by means of the narrow strips referred to. It will also be observed that my construction affords an effective means for mechanically holding the parts of the radiator construction together and that the solder is not depended upon for mechanical strength but merely to make the joints water-tight. Furthermore, my construction affords an effective means for directing the solder to the required places in securing the parts of the radiator together and the channels retain the solder in its proper position in a highly effective manner. Furthermore, my construction presents a pleasing appearance on account of the substantial and finished effect produced by the strips 27, 28, 34 and 31'.

As a result of the construction described,

the adjacent walls of any adjacent pair of units of the radiator form a water tube continuous vertically from the header 10 to the header 11 and the ends of the unit construction, form the bottom of the header 10 and the top of the header 11, water being therefore permitted to flow only through the tubes referred to. Furthermore, it will be observed that as a result of my construction each water tube has extending from it at intervals a pair of pockets opening from opposite sides of the water tube at the same height for receiving a portion of the water flowing through the tubes to assist in cooling the same by increasing the surface of the water in the tube exposed to the cooling action. It will also be noted that the water tubes are all alike, the only difference between them being in their manner of disposition in the radiator, alternate ones of said tubes being reversed relatively to the intermediate ones thereof, so that the pockets on one set of tubes are disposed between the pockets of the other set of tubes. Each water tube, it will be observed, has a uniform open path for water flow from top to bottom, of the same width from the front to the rear wall of the radiator, so that there is no obstruction to the flow of water through the tubes.

While I have shown my invention in the particular embodiments shown and described herein, I do not, however, limit myself to these exact constructions as I may employ equivalents thereof without departing from the spirit of my invention.

What I claim is:

1. In an automobile radiator, upper and lower water headers, water tubes extending vertically between the headers, said water tubes being formed from thin sheet metal and having horizontally extending pockets, whereby the assembled water tubes form a "honeycomb" construction, channels formed along the upper and lower edges of the assembled water tubes and along the lower and upper edges of the upper and lower water headers, respectively, and narrow strips of thin sheet metal engaging said channels and connecting the assembled water tubes with said headers, whereby said strips may be cut and the assembled water tubes removed from the headers without injury to the water tubes or headers.

2. In an automobile radiator, upper and lower water headers, water tubes extending vertically between the headers, said water tubes being formed from thin sheet metal and having horizontally extending pockets, whereby the assembled water tubes form a "honeycomb" construction, channels formed along the upper and lower edges of the assembled water tubes and along the lower and upper edges of the upper and lower water headers, respectively, and narrow

- strips of thin sheet metal engaging said channels and connecting the assembled water tubes with said headers, whereby said strips may be cut and the assembled water tubes removed from the headers without injury to the water tubes or the headers, the sheets of thin metal forming each water tube having channels formed along their edges, and narrow strips of thin sheet metal entering said channels and connecting said sheets together, whereby said sheets may be separated from each other by cutting through said strips without injury to said sheets.
3. In an automobile radiator, upper and lower water headers, water tubes extending vertically between the headers, said water tubes being formed from thin sheet metal and having horizontally extending pockets, whereby the assembled water tubes form a "honeycomb" construction, the sheets of thin metal forming each water tube having channels formed along their edges, and narrow strips of thin sheet metal entering said channels and connecting said sheets together, whereby said sheets may be separated from each other by cutting through said strips without injury to said sheets.
4. In an automobile radiator, upper and lower water headers, water tubes extending vertically between the headers, said water tubes being formed from thin sheet metal and having horizontally extending pockets, whereby the assembled water tubes form a "honeycomb" construction, the sheets of thin metal forming each water tube having channels formed along their edges, and narrow strips of thin sheet metal entering said channels and connecting said sheets together, whereby said sheets may be separated from each other by cutting through said strips without injury to said sheets, the ends of said pockets being closed by flaps extending from said sheets and folded over each other.
5. In an automobile radiator, upper and lower water headers, water tubes extending vertically between the headers, said water tubes being formed from thin sheet metal and having horizontally extending pockets, whereby the assembled water tubes form a "honeycomb" construction, channels formed along the upper and lower edges of the assembled water tubes and along the lower and upper edges of the upper and lower water headers, respectively, and narrow strips of thin sheet metal engaging said channels and connecting the assembled water tubes with said headers, whereby said strips may be cut and the assembled water tubes removed from the headers without injury to the water tubes or the headers, the sheets of thin metal forming each water tube having channels formed along their edges, and narrow strips of thin sheet metal entering said channels and connecting said sheets together, whereby said sheets may be separated from each other by cutting through said strips without injury to said sheets.

rated from each other by cutting through said strips without injury to said sheets, the ends of said pockets being closed by flaps extending from said sheets and folded over each other.

70

6. A radiating unit for an automobile radiator, consisting of two similar sheets of thin metal each sheet having folded pockets extending nearly or quite into engagement with the other sheet, the pockets on one sheet alternating with the pockets on the other sheet, channels formed on the end portions of said sheets, and narrow strips of thin sheet metal entering said channels and securing said sheets together, whereby said sheets may be separated from each other without injury to said sheets by cutting through said strips, said sheets having folded flaps at the ends of said pockets to fold over each other to close the ends of said pockets.

80

7. A radiating unit for an automobile radiator consisting of two similar sheets of thin metal each sheet having folded pockets extending nearly or quite into engagement with the other sheet, the pockets on one sheet alternating with the pockets on the other sheet, said sheets being connected together at their ends and provided along their edges with channels, whereby two of such units may be connected together by narrow strips of thin sheet metal engaging said channels, said sheets having folded flaps at the ends of said pockets to fold over each other to close the ends of said pockets.

90

8. In an automobile radiator, upper and lower water headers, an assembly of water tubes between said headers, channels formed along the upper and lower edges of the assembly of water tubes and along the lower and upper edges of the upper and lower water headers respectively, and narrow strips of thin sheet metal engaging said channels to hold the parts together whereby the said assembly of water tubes may be separated from said headers by cutting through said strips without injury to said assembly or said headers.

100

9. A core for an automobile radiator comprising water tubes extending vertically, said water tubes being formed from thin sheet metal having horizontal extensions, whereby the assembled water tubes form a "honeycomb" construction, the sheets of thin metal forming each water tube having channels formed along their edges, and narrow strips of thin sheet metal entering said channels and connecting said sheets together, whereby said sheets may be separated from each other by cutting through said strips without injury to said sheets.

115

10. A core for an automobile radiator comprising water tubes extending vertically, said water tubes being formed from thin sheet metal having horizontal extensions,

120

130

whereby the assembled water tubes form a "honeycomb" construction, the sheets of thin metal forming each water tube having channels formed along their end portions, and 5 narrow strips of thin sheet metal entering said channels to connect adjacent sheets of adjacent tubes together, whereby said tubes

may be separated from each other without injury to said sheets by cutting through said strips.

In witness whereof, I hereunto subscribe my name this 8th day of May, A. D. 1916.

10

JOE ERLICH.
